Primary Examiner — Kelley A Donnelly(74) *Attorney, Agent, or Firm* — Locke Lord LLP; Daniel J. Fiorello(57) **CLAIM**

The ornamental design for a double tab shelf, as shown and described.

DESCRIPTION

FIG. 1 is a perspective view of an embodiment of the double tab shelf of the subject disclosure;

FIG. 2 is a front side elevation view of the double tab shelf of FIG. 1;

FIG. 3 is a rear side elevation view of the double tab shelf of FIG. 1;

FIG. 4 is a left side elevation view of the double tab shelf of FIG. 1;

FIG. 5 is a right side elevation view of the double tab shelf of FIG. 1;

FIG. 6 is a top plan view of the double tab shelf of FIG. 1; and,

FIG. 7 is a bottom plan view of the double tab shelf of FIG. 1.

The broken lines shown in the drawings do not form part of the claimed design.

1 Claim, 5 Drawing Sheets(56)
